UNITED STATES PATENT OFFICE.

ALBERT E. SCHAAF AND HENRY G. FISKE, OF TOLEDO, OHIO.

DESIGN FOR A DASH FOR AUTOMOBILES.

No. 38,096.

Specification for Design.

Patented June 19, 1906.

Application filed March 13, 1906. Serial No. 305,917. Term of patent 7 years.

To all whom it may concern:

Be it known that we, ALBERT E. SCHAAF and HENRY G. FISKE, citizens of the United States, residing in Toledo, in the State of Ohio, have invented a certain new, original, and ornamental Design for a Dash for Automobiles, of which the following is a specification, reference being had to the accompanying drawing, forming a part hereof.

This invention consists in the ornamental design for a dash for automobiles, as shown

in the accompanying drawing, which is a view in perspective of such a dash embodying the invention.

We claim—

The ornamental design for a dash for automobiles, as shown.

ALBERT E. SCHAAF.
HENRY G. FISKE.
